UNITED STATES PATENT OFFICE.

RYERSON W. HILLIKER, OF KANSAS CITY, KANSAS.

BAKE-OVEN FOR GAS OR GASOLENE STOVES.

SPECIFICATION forming part of Letters Patent No. 700,045, dated May 13, 1902.

Application filed September 10, 1901. Serial No. 74,968. (No model.)

To all whom it may concern:

Be it known that I, RYERSON W. HILLIKER, a citizen of the United States, residing at Kansas City, in the county of Wyandotte and 5 State of Kansas, have invented certain new and useful Improvements in Bake-Ovens for Gas or Gasolene Stoves; and I do declare the following to be a full, clear, and exact description of the invention, such as will enable 10 others skilled in the art to which it appertains to make and use the same.

The invention relates to a bake-oven for gas or gasoline stoves.

The object of the invention is to provide a 15 device of this character which shall be simple of construction, durable in use, comparatively inexpensive of production, which may be used for baking or steaming foods, and which will perform its duties in an effective, 20 economical, and satisfactory manner.

With these and other objects in view the invention consists of certain novel features of construction, combination, and arrangement of parts, which will be hereinafter 25 more fully described, and particularly pointed out in the appended claims.

In the accompanying drawings, Figure 1 is a perspective view of the invention. Fig. 2 is a similar view showing a double oven, 30 which consists of two single ovens connected together. Fig. 3 is a vertical sectional view; and Fig. 4 is a transverse sectional view through one oven and its door, showing in full lines the door open and in dotted lines the 35 door closed.

Referring now more particularly to the drawings, 1 denotes the oven-casing, provided with a top 2, consisting of two parts *a* and *b*, spaced apart and lined with a strip of asbestos *c*, the part *a* having draft-openings *a'* at the center and the part *b* having draft-openings *a''* near 40 its periphery or edge. This casing is provided with a door-opening 3 and with an inwardly-projecting annular flange 4. To the side of 45 the casing is hinged a door 5, preferably made of spring metal and having a curvature of greater radius than that of the casing. In order to engage the latch 6 of said door with the keeper 7 of said casing, said door must 50 be sprung inward to make its curvature correspond with that of the casing, and upon

disengaging the door-latch from the keeper of said casing the spring of the door will suddenly swing it open, thus making it practically automatic in its opening movement. 55

8 denotes a deflector secured within the casing at a slight distance above the central opening 9 therein, formed by the annular flange and made any desired shape. As shown, it is conical and is suitably lined with 60 asbestos 10.

11 and 12 denote, respectively, the upper and lower oven-shelves, each of which is provided with angular supporting-legs 13 and 14, those of the upper shelf being longer than 65 those of the lower shelf and projecting laterally from the edge of the shelf a sufficient distance to engage the sides of the casing, so that when in position one above the other there will be an air-space formed between the 70 sides of the casing and the edges of the shelf to permit of the free circulation of heated air upwardly, and at the same time these legs hold the shelves in proper position with respect to each other and the sides of the casing 75 and prevent the shifting of said shelves laterally.

When the device is used as a bake-oven, the articles of food are placed upon the shelves and the burner of the stove adjusted to supply the desired amount of heat. The hot air passes up through the opening in the bottom of the oven formed by the inwardly-projecting annular flange around the edges of the lower shelf, circulates in the space between 80 the two shelves, thence passes up around the edge of the upper shelf and over the same, and is then drawn through the central portion of the top, through which it escapes through the perforations into the space formed between 85 the two parts of the top, and finally passes out through the openings *a''*.

When the device is used as a steamer, the lowermost shelf may be removed and a pan or receptacle of water placed in the oven upon 90 the inwardly-projecting annular flange and over the central opening and the flame of the stove, and thus arranged articles of food may be expeditiously cooked by steam. 95

The ovens may be made in single or double 100 form, as desired. When arranged in duplex form, the ovens are connected together by

sheets of metal *w*, screwed, riveted, or otherwise suitably secured to the sides of the oven, and provided with a bail or handle *x*.

From the foregoing description, taken in connection with the accompanying drawings, the construction, mode of operation, and advantages of my invention will be readily understood without requiring a more extended explanation.

10 Various changes in the form, proportion, and details of construction may be made within the scope of the invention without departing from the spirit or sacrificing any of the advantages thereof.

15 Having thus described my invention, what I claim, and desire to secure by Letters Patent, is—

1. In an oven of the character described, the combination with the casing provided with 20 an inwardly-projecting annular flange leaving a central draft-opening, a deflector secured to said flange above said opening, and shelves in said opening and provided with supporting-legs, the supporting-legs of the 25 uppermost shelf being longer than those of the lowermost shelf, the supporting-legs of said shelves extending laterally from the edges of said shelves and engaging the sides

of the oven to prevent lateral shifting of said shelves, substantially as set forth.

2. In an oven of the character described, the combination with the oven-casing having a top consisting of two parts spaced apart, one of said parts being provided with draft-openings at the center and the other part being provided with draft-openings near its periphery, an inwardly-projecting annular flange secured to the lower end of the casing and leaving a central draft-opening, a deflector secured to said flange above said opening, and shelves in said opening and provided with supporting-legs, the supporting-legs of the uppermost shelf being longer than those of the lowermost shelf, the supporting-legs of said shelves extending laterally from the 45 edges of said shelves and engaging the sides of the oven to prevent lateral shifting of said shelves, substantially as set forth.

In testimony whereof I have hereunto set my hand in presence of two subscribing witnesses.

RYERSON W. HILIKER.
